WAYSIDE INDICATOR FOR RAILWAY
MOTOR CARS

Arthur W. Fisher, Forest Hills, and Wesley B. Wells, Wilkinsburg, Pa., assignors to The Union Switch and Signal Company, Swissvale, Pa., a corporation of Pennsylvania

Application March 27, 1948, Serial No. 17,436

12 Claims. (Cl. 177—329)

1

This invention relates to a signal for producing two contrasting indications of the color position type, and especially to signals of the type described for use on railways.

Railroads commonly use small light-weight motor cars for carrying maintenance men and others. These cars are operated independently of the regular railway signal systems, in order that they may not delay the passage of trains. The men on the cars are therefore required to watch out for approaching trains and remove the car from the rails in time to avoid collisions. Under certain conditions, it is very difficult for the motor car riders to be sure that no train is within a dangerously close distance of them. For example, where trains are operated at very high speeds, they may approach the motor car so rapidly that it is difficult to remove the car from the track between the time the train is first sighted and the time it reaches the car. A hazard also exists at blind curves and similar locations even where low speed trains are operated. In other cases, there may be long stretches of track such as trestles or bridges where there is not sufficient room at the wayside to permit removal of the motor car from the track. In such a location, the motor car must have time to reach the end of the stretch before it can possibly be removed.

Because of these hazards, it is very desirable to provide indicators for informing the occupants of a motor car that a train is approaching and that they should therefore remove the car from the rails as quickly as possible. Such indicators may be spaced at intervals along the wayside, particularly at dangerous points. These indicators are not required to be as large or elaborate as the regular wayside signals, but on the other hand are required to be small and inexpensive because of the relatively greater number of signals required. The indicators must, however, be very reliable and must give a positive, unmistakable indication.

It is therefore an object of our invention to provide a small, inexpensive indicator for use on railways to indicate to motor car operators that a train is approaching.

Another object of our invention is to provide an improved device for giving two separate and distinct signal indications.

Since such indicators are necessary at locations remote from any power supply, another object is to provide an improved indicator which does not require a source of illumination within itself. A further object is to provide an indicator

2

having reflecting indicia which make the indicator readily visible at night to persons riding on a vehicle equipped with a light.

It is a further object of our invention to provide an improved device for giving two separate signal indications which are distinctive both as to color and as to position.

Another object is to provide an improved supporting and operating structure for a rotatable signal member. A further object is to provide such a structure which is improved from the standpoint of accessibility for inspection and repair.

We accomplish the foregoing objects of our invention by providing a combined relay and indicator unit including a relay of conventional form controlled by suitable circuits so as to be responsive to the presence of a train within the desired control limits. The armature of this relay

20 is connected to a novel and distinctive indicator.

The indicator comprises a white screen having a central black spot, and four apertures of substantially the same area as the spot located at equal distances to the left, right, above and below the spot. Behind the screen is mounted a white disc rotatable about an axis passing through the center of the black spot on the screen. This disc carries two diametrically opposite pairs of spots. One pair of spots is red. The other is colored

30 green and is located on a diameter spaced by an angle of 45 degrees from the diameter on which the red spots lie. The disc is carried by a shaft connected to the relay armature. When the relay winding is deenergized, indicating that a train is approaching, the armature rotates the shaft and thereby the disc to a position in which the two red spots on the disc are visible through the apertures in the screen located on the left and right-hand sides of the black central spot. The

35 aspect of the signal to an observer is therefore a horizontal line of three spots, the end spots being red and the center one black. When no train is approaching, the relay is energized and

40 attracts its armature, thereby rotating the disc to move the red spots behind the screen and to bring the green spots into alignment with the two apertures above and below the central black spot. The aspect of the signal is then a vertical

45 row of three spots, the top and bottom spots being green, and the center one black. We prefer to cover the colored spots on the disc with reflecting material, so as to increase the visibility of the indicator at night.

50 Other objects and characteristic features of our

invention will become apparent as the description proceeds.

We shall describe one form of indicator embodying our invention, and shall then point out the novel features thereof in claims.

In the accompanying drawings, Fig. 1 is an elevational view of an indicator casing in which is mounted an indicator embodying our invention. Fig. 2 is a side elevational view of the indicator of Fig. 1. Fig. 3 is an elevational view of the indicator unit of Fig. 1, removed from the casing, and with certain parts broken away to permit a better view of the interior mechanism. Fig. 4 is a side elevational view of the indicator unit of Fig. 3, with certain parts broken away.

Referring to the drawings, there is shown a housing 1 having a socket 2 for mounting on a conventional supporting post 3. The housing has a hinged back cover 4 for access to the interior. Inside the housing is a mounting plate 5 which supports by means of spring supports 6 a relay housing generally indicated at 7 and including a base 8, a transparent casing 9, and an insulating top plate 10.

Mounted on the upper surface of the top plate 10 is a pair of relay coils 11 having core structures 12 (see Fig. 3) which extend downwardly within the casing 9 and cooperate with an armature 13. The armature 13 carries an insulating bracket 14 which supports a number of electrical contacts 15. The contacts 15 are connected electrically to terminal posts 16 of conventional form, carried on the top plate 10.

The armature 13 also carries an L-shaped arm 17 which extends upwardly through an aperture 10a in the top plate 10. Mounted on the top plate 10 so as to cover the aperture 10a through which the arm 17 passes is a casing 18. The casing 18 is screwed and sealed to the top plate 10.

A bracket 19 is attached to one side of the interior of casing 18, and has a pair of spaced lugs 19a supporting trunnions 19b on which is rotatably mounted a shaft 20. The shaft 20 carries an arm 21 connected by a link 22 to the upper end of arm 17. A yoke 23 has its bight fixed on the shaft 20 and its arms extending forwardly of the casing 18, spanning the front lug 19a and the front trunnion 19b. At its forward end, the yoke 23 carries a disc 24. The front side of disc 24 is white or light colored and has two diametrically opposite red spots 24a and two diametrically opposite green spots 24b. It should be noted that the green spots 24b are located on a diameter of the disc 24 which is spaced by an angle of 45 degrees from the diameter on which the red spots 24a are located.

The disc 24 is apertured at 24c to permit access to front trunnion 19b for inspection, adjustment and repair. The casing 18 has an aperture 18a aligned with the rear trunnion 19b and covered by a removable glass window 18b, so that the rear trunnion is similarly accessible for inspection, adjustment and repair.

A screen 25 is fastened at its edges to the casing 18 so as to overlie the rotatable disc 24. The screen 25 is provided with a central black spot 25a, which contrasts with a background having the same color as disc 24. The screen 25 is also provided with four apertures 25b, which are of substantially the same area as the black spot 25a, and are spaced at equal distances to the left, right, above and below the spot 25a.

The screen 25 and disc 24 are enclosed by a glass roundel of conventional form, indicated at

26, which is attached at its edges to the housing 18 by means of a frame 27.

The relay windings 11 are intended to be de-energized or energized according as a train is or is not approaching the signal within control limits which are determined by the conditions at the signal location. As long as the windings 11 are energized, the armature 13 is held in the attracted position shown in Fig. 3. The armature 13 acts through arm 17, link 22 and crank arm 21 to hold the disc 24 in the position shown in Fig. 3 wherein the green spots 24b are visible through the apertures 25b above and below the central black spot 25a. The signal aspect then presented to an observer is a vertical line of three spots, the upper and lower spots being green and the central one black.

When a train enters the control limits of the signal, the windings of relay 11 are deenergized, so that it drops its armature 13. The dropping of armature 13 acts through arm 17, link 22 and crank arm 21 to rotate the shaft 20 and the disc 24 through an angle of 45 degrees. This moves the green spots 24b out of sight behind the screen 25, and moves the red spots 24a into alignment with the apertures 25b located respectively at the left and right of the black spot 25a. The signal aspect then presented to an observer is a horizontal line of three spots, the end spots being red and the middle spot black, as shown in Fig. 1.

It may therefore be seen that the two signal aspects presented by our improved signal are distinctive both as to color and as to position.

We prefer to provide the green and red spots with reflecting surfaces so that they may be more readily visible at night. This is especially advantageous with a signal such as this, which has no source of illumination of its own, and depends for night-time observation upon light directed at it from an external source, such as a light carried on a motor car.

Although we have herein shown and described only one form of signal embodying our invention, it is understood that various changes and modifications may be made therein within the scope of the appended claims without departing from the spirit and scope of our invention.

Having thus described our invention, what we claim is:

1. An indicator including a screen having a central colored spot and four apertures having areas substantially equal to that of the spot and spaced equal distances from the spot respectively to the left, right, and above and below the spot, a rotatable shaft behind the screen and aligned with the spot, a disc on the shaft having a background substantially the same color as the screen and fixed on the shaft for rotation therewith, said disc having two pairs of diametrically opposite spots colored to contrast with the background located on diameters separated by an angle of 45 degrees and at radial distances from the shaft equal to the distance between the spot on the screen and the apertures therein, each of said pairs of spots being of a different color than the other pair, and means for rotating said disc between a first position wherein one pair of spots on the disc is visible through the apertures at the left and right of the screen spot so that a horizontal row of three spots is visible to an observer, and a second position spaced 45 degrees from the first position wherein the other pair of spots on the disc is visible through the apertures

above and below the screen spot so that a vertical row of three spots is visible to an observer.

2. An indicator including a light-colored screen having a central black spot and four apertures having areas substantially equal to that of the spot and spaced equal distances from the spot respectively to the left, right, and above and below the spot, a rotatable shaft behind the screen and aligned with the spot, a disc on the shaft having a background substantially the same color as the screen and fixed on the shaft for rotation therewith, said disc having two pairs of diametrically opposite spots colored to contrast with the background located on diameters separated by an angle of 45 degrees and at radial distances from the shaft equal to the distance between the spot on the screen and the apertures therein, one of said pairs of spots being red and the other being green, and means for rotating said disc between a first position wherein the pair of red spots on the disc is visible through the apertures at the left and right of the screen spot so that a horizontal row of three spots is visible to an observer, and a second position spaced 45 degrees from the first position wherein the pair of green spots on the disc is visible through the apertures above and below the screen spot so that a vertical row of three spots is visible to an observer.

3. An indicator including a screen having a central colored spot and four apertures having areas substantially equal to that of the spot and spaced equal distances from the spot respectively to the left, right, and above and below the spot, a rotatable shaft behind the screen and aligned with the spot, a disc on the shaft having a background substantially the same color as the screen and fixed on the shaft for rotation therewith, said disc having two pairs of diametrically opposite spots colored to contrast with the background located on diameters separated by an angle of 45 degrees and at radial distances from the shaft equal to the distance between the spot on the screen and the apertures therein, and means for rotating said disc between a first position wherein one pair of spots on the disc is visible through the apertures at the left and right of the screen spot so that a horizontal row of three spots is visible to an observer, and a second position spaced 45 degrees from the first position wherein the other pair of spots on the disc is visible through the apertures above and below the screen spot so that a vertical row of three spots is visible to an observer.

4. An indicator including a screen having a central colored spot and four apertures having areas substantially equal to that of the spot and spaced equal distances from the spot respectively to the left, right, and above and below the spot, a rotatable shaft behind the screen and aligned with the spot, a disc on the shaft having a background substantially the same color as the screen and fixed on the shaft for rotation therewith, said disc having two pairs of diametrically opposite spots colored to contrast with the background located on diameters separated by an angle of 45 degrees and at radial distances from the shaft equal to the distance between the spot on the screen and the apertures therein, reflecting material covering each of the spots on the disc, and means for rotating said disc between a first position wherein one pair of spots on the disc is visible through the apertures at the left and right of the screen spot so that a horizontal row of three spots is visible to an observer, and a second position spaced 45 degrees from the first position

wherein the other pair of spots on the disc is visible through the apertures above and below the screen spot so that a vertical row of three spots is visible to an observer.

5. An indicator including a screen having four apertures having substantially equal areas and spaced equal distances respectively to the left, right, and above and below a point on the screen, a disc behind the screen and rotatable about an axis passing through said point, said disc having a background substantially the same color as the screen, and two pairs of diametrically opposite spots colored to contrast with the background, said spots being located on diameters separated by an angle of 45 degrees and at radial distances from the axis equal to the distance between the point on the screen and said apertures therein, each of said pairs of spots being of a different color than the other pair, and means for rotating said disc between a first position wherein one pair of spots on the disc is visible through the apertures at the left and right of said point on the screen, and a second position spaced 45 degrees from the first position wherein the other pair of spots on the disc is visible through the apertures above and below the point on said screen.

6. An indicator including a screen having two apertures with substantially equal areas and spaced equal distances along horizontal and vertical lines respectively from a point on the screen, a disc behind the screen and rotatable about an axis passing through said point, said disc having a background substantially the same color as the screen and having two spots colored to contrast with the background located on radial lines separated by an angle of 45 degrees and at radial distances from the axis equal to the distance between said point on the screen and the apertures therein, each of said spots being of a different color than the other, and means for rotating said disc between a first position wherein one spot on the disc is visible through the aperture horizontally spaced from said point on the screen, and a second position spaced 45 degrees from the first position wherein the other spot on the disc is visible through the other aperture.

7. An indicator including a screen having a central colored spot and two apertures having areas substantially equal to that of the spot and spaced equal distances along horizontal and vertical lines respectively from the spot, a disc behind the screen and rotatable about an axis passing through the spot, said disc having a background substantially the same color as the screen and two spots colored to contrast with the background located on radial lines separated by an angle of 45 degrees and at radial distances from the shaft equal to the distance between the spot on the screen and the apertures therein, each of said spots being of a different color than the other, and means for rotating said disc between a first position wherein one spot on the disc is visible through the aperture horizontally spaced from the screen spot so that a horizontal row of two spots is visible to an observer, and a second position spaced 45 degrees from the first position wherein the other spot on the disc is visible through the aperture vertically spaced from the screen spot so that a vertical row of two spots is visible to an observer.

8. An indicator comprising a relay having a winding and an armature operated thereby, a housing enclosing said armature, a top plate for said housing, said top plate having an aperture therein, a casing mounted on the upper surface

of said top plate so as to cover said aperture, a transparent panel in one side of said casing, a screen having two apertures therein behind said panel, an indicator member behind the screen of substantially the same color as the screen and having two spots thereon of different colors which contrast with the screen color, means movably supporting the indicator member, and a mechanical connection between the relay armature and the indicator member so that the signal member is in a first position wherein one spot is visible through one aperture when the relay winding is deenergized and is moved to a second position wherein the other spot is visible through the other aperture when the relay winding is energized, thereby providing separate indications of the different conditions of energization of the winding, which indications are distinctive both as to color and position.

9. An indicator comprising a casing, a transparent removable panel in one side of the casing, a screen behind said panel having a plurality of spaced apertures therein, said screen being removable when the panel is removed, an indicator disc rotatable behind said screen and having on its surface indicia which are visible through different ones of said apertures in different positions of the disc, a shaft in said casing aligned with the axis of the disc, a pair of spaced trunnions mounted in the casing and supporting the ends of the shaft, a yoke having its bight attached to the shaft between the trunnions and its arms spanning one trunnion and attached to the disc so that the disc is rotatably supported by the shaft and yoke, said disc having an aperture therein to permit access to said one trunnion, said disc aperture being normally covered by said screen, said casing having an aperture therein aligned with the other trunnion, and a removable window for said last-mentioned aperture to permit access to the other trunnion.

10. An indicator comprising a relay having a winding and an armature operated thereby, a housing enclosing said armature, a top plate for said housing, said top plate having an aperture therein, a casing mounted on the upper surface of said top plate so as to cover said aperture, a transparent removable panel in one side of the casing, a screen behind the panel having a white background, a central black spot, and four apertures whose areas are substantially equal to that of the spot and spaced equal distances from the spot respectively to the left, right and above and below the spot, a rotatable shaft in the casing and aligned with the spot, a pair of spaced trunnions mounted in the casing and supporting the ends of the shaft, a yoke having its bight attached to the shaft between the trunnions and its arms spanning the trunnion nearest the screen, an indicator disc mounted on the ends of the arms for rotation with the shaft and yoke, said disc having an aperture therein aligned with said one trunnion and said black spot on the screen, said screen being removable when the panel is removed to permit access to said one trunnion through said aperture, said casing having an aperture therein aligned with the other trunnion, a removable window for said last-mentioned aperture to permit access to the other trunnion, said disc having a pair of diametrically opposite

5 red spots and a pair of diametrically opposite green spots located on diameters separated by an angle of 45 degrees and at radial distances from the shaft equal to the distance between the black spot on the screen and the apertures therein, and a mechanical connection between the relay armature and the indicator disc so that when the relay winding is deenergized the red spots are aligned with the apertures at the left and right 10 of the black spot and the indicator presents to an observer an aspect consisting of a horizontal row of three spots, the end spots being red and the center spot black, and when the relay winding is energized the armature rotates the indicator disc to move the red spots behind the screen and align the green spots with the apertures above and below the black spot, so that the indicator presents to an observer an aspect consisting of a vertical row of three spots, the top and bottom spots being green and the center spot black.
